ROPE TWISTING MACHINE

Richard Kososhuk, Eau Claire, Wis.

Application October 12, 1933, Serial No. 693,334

2 Claims. (Cl. 117—48)

This invention appertains to twisting machines for forming cotton cord twist utilized in making so-called blow-out proof pneumatic vehicle tires.

Much thought has been given by tire manufacturers to the making of blow-out proof tires and cotton cord twist is now employed, which has for one of its functions to reduce the transmission of heat. This cord consists of strands of carded long staple Sea Island cotton. These 10 carded cotton strands are received from the mill on spools and considerable difficulty is experienced in uniting the strands together to form the cord twist. At the present time, even in the best cord twist, the strands are only slightly twisted 15 or matted together which gives an inferior product.

It is therefore one of the primary objects of my invention to provide a machine which will effectively twist the carded cotton strands together and give the cord any amount of twist (tight or loose) which may be desired in a particular tire construction.

Another salient object of my invention is to provide a novel machine which will receive the 25 ordinary spools of carded cotton strands and effectively twist the strands together to form the desired cord and wind the twisted cord upon a receiving spool or reel.

A further important object of my invention is 30 the provision of novel means for arranging the spool carriers on the twisting wheel, whereby a plurality of outer cotton strands will be twisted about a central strand.

A further object of my invention is the provision of a novel guide sleeve for receiving all 35 of the strands from the twisting wheel, the sleeve acting in the dual capacity of guiding the strands and holding the strands during the twisting operation.

40 A further object of my invention is the provision of a novel friction means for winding the twisted strands upon the receiving spool, the receiving spool being mounted upon a novel carrier whereby the spool is free to raise and lower relative to the friction drive, as the diameter of the 45 spool increases incident to the winding of the cord twist thereon.

A further object of my invention is the provision of novel means for mounting the spools 50 carrying the carded cotton strands upon the twisting wheel, whereby the same can be readily and quickly placed on or removed from the wheel.

A still further object of my invention is to provide a cord twisting machine of the above character, which will be durable and efficient in use,

one which will be simple and easy to manufacture and one which can be placed upon the market at a low cost and produce a maximum amount of cord twist in a minimum amount of time.

With these and other objects in view, the invention consists in the novel construction, arrangement and formation of parts, as will be hereinafter more specifically described, claimed and illustrated in the accompanying drawings, in which:—

Figure 1 is a longitudinal section through my improved machine taken substantially on the line 1—1 of Figure 2, looking in the direction of the arrows.

Figure 2 is a top plan view of my improved machine with parts of the twisting wheel shown broken away and in section to illustrate structural details.

Figure 3 is a transverse sectional view through the machine taken substantially on the line 3—3 of Figure 2, looking in the direction of the arrows, illustrating the twisting wheel.

Figure 4 is an enlarged fragmentary vertical section illustrating the novel guide sleeve for the cord twist.

Figure 5 is an enlarged fragmentary detail view, illustrating the means employed for detachably holding the receiving spool in place.

Referring to the drawings in detail, wherein similar reference characters designate the corresponding parts throughout the several views, the letter A generally indicates my improved cord twisting machine which comprises a main base frame 10, which can be mounted upon suitable standards or legs, if so desired. At one end of the frame 10 I arrange the novel twisting wheel 11 and at the opposite end of the frame I dispose the receiving reel 12 and the friction winding means 13 therefor.

The novel twisting wheel 11 includes a relatively 40 large disc 14, the axial center of which is provided with a hub 15 which is in turn keyed or otherwise secured, as at 16, to a driven shaft 17. The driven shaft 17 is rotatably mounted in bearings 18 mounted on bearing standards 19 which 45 extend transversely of the frame. This driven shaft 17 has keyed or otherwise secured thereto a relatively large pulley 20, whereby the shaft 17 may be turned from a suitable power shaft (not shown).

Connected to one face of the disc 14 is a central spool carrier 21. Disposed radially around the central spool carrier 21 at equidistantly spaced points are outer spool carriers 22. The central spool carrier 21 and the outer spool car-

riers 22 are all of the same construction and each embody spaced side brackets 23 bolted or otherwise secured to the disc 14, and the brackets are provided with slots 24 for receiving the terminals 5 of the movable spindles 25. These spindles 25 extend through the hubs 26 of the spools 27 upon which the carded cotton strands are wound. The ends of the spool hubs 26 are each provided with end flanges 29.

10 In order to hold the spools on their bearing brackets, the ends of the spools may carry detachable rings 30 to which are secured the outer ends of contractile coil springs 31. The inner ends of the springs are secured to the disc 14 or 15 to the adjacent brackets 23. This creates a tension for normally drawing the spools inwardly toward the disc 14 and the spindles 25 allow the free rotation of the spools on the disc. Additional catches 32 can be employed and as 20 shown, these catches are pivoted as at 33 to adjacent bearing brackets 23 and are of a Z-shape and are wedged over the rings 30 so as to prevent the accidental displacement of the rings from off of the spindle terminals.

25 Arranged in front of the main or large disc 14 is a second axially disposed disc 34. The disc 34 functions as a guide for the various strands 28 of the carded cotton, and the disc 34 is arranged in spaced parallel relation to the disc 11. 30 Suitable supporting arms 35 connect the discs 14 and 34 together. The disc 34 at its axial center is provided with a guide opening 36 through which is threaded the strand 28 from the central spool and the periphery of the disc carries 35 at equidistantly spaced points guide eyes 37 for receiving the cotton strands from the outer spools.

From the description so far, it can be seen that as the twisting wheel 11 rotates, the spools will 40 be rotated therewith and as the center spool is arranged at the axial center of the disc 14, a center cotton strand will be provided and the cotton strands from the outer spools will be twisted thereabout.

45 In order to bring about the proper twisting of the various strands, I provide a novel guide sleeve 38 which is of an elongated character. The front end of the guide sleeve 38 is provided with a funnel-shaped entrance or flared throat 39 for facilitating the guiding of the cotton strands into the sleeve. If desired, the rear end of the guide sleeve 38 can be slightly flared as at 50 40 to facilitate the pulling of the twisted cord from the guide sleeve.

55 This guide sleeve 38 is received within a collar 41 and the sleeve 38 may be adjusted within certain limits within said collar and held in its adjusted position by means of a set screw 42. The set screw 42 can be carried by the collar 41 for impinging against the guide sleeve. The guide sleeve 41 is rigidly mounted upon a vertical standard 43 and this standard is adjustably mounted within a tubular supporting column 44. A set screw 45 can be provided for holding the standard 43 in its preferred adjusted position. 60 The lower end of the column 44 is provided with a collar 46 which is in turn mounted upon a substantially inverted U-shaped bracket 47. The lower ends of the bracket 47 are received in cuffs 70 48 which are riveted or otherwise fastened to the base 10. The collar 46 is slidably mounted on the bracket 47 and can be held in an adjusted position by means of the set screw 49.

75 By providing this type of support for the guide sleeve, it is to be noted that the guide sleeve can

be adjusted both vertically and longitudinally to bring about the desired results and it is essential that the guide sleeve be in axial alignment with the centers of the discs 14 and 34.

As the twisted cord leaves the guide sleeve 38, 5 the same is wound upon the receiving spool 12 by means of the friction winding device 13 heretofore mentioned. The receiving spool 12 includes the hub sleeve 50 carrying the end flanges 51 and the spool is rotatably mounted upon a shaft 52 10 which is inserted through the hub of the spool. The ends of the shaft 52 extend through bearing members 53. One end of the shaft 52 is provided with a flange 54 against which normally rests a spring actuated catch 55, whereby the accidental 15 displacement of the shaft 52 is prevented.

As clearly shown in Figures 1 and 2 of the drawings, the receiving spool is mounted directly in rear of the guide sleeve 38, so as to receive the 20 twisted cord from said guide sleeve.

The bearings 53 are carried by inverted U-shaped supporting brackets 56. These brackets 59 extend longitudinally of the frame in spaced parallel relation and the same can be connected together by a transversely extending brace bar 51. 25 The depending legs 58 of the brackets are of tubular construction and are slidably mounted upon upright standard 59. These standards are securely bolted to the frame 10. Contractile coil springs 60 connect the brackets 56 with the frame 30 and normally tend to draw the brackets downwardly toward the frame and the receiving spool against the friction winding means 13 which will now be described.

The friction winding means 13 comprises a 35 friction drum 61 keyed or otherwise secured to a driven shaft 62. This shaft 62 is rotatably mounted in bearings 63 carried by bearing brackets 64, which are bolted or otherwise secured to the frame 10. One end of the shaft 52 40 has keyed or otherwise secured thereto a pulley wheel 65, whereby the drum can be actuated from a drive shaft. The friction drum 61 has its periphery covered with a face of friction material indicated by the reference character 66, and the 45 spool hub with its windings rests against said friction covering.

It is to be noted that the pulley 65 is of a less size than the pulley 20 of the twisting wheel 11 and these pulleys 20 and 65 are adapted to be 50 driven synchronously from a drive shaft and consequently, the friction drum 61 will be driven at a lower rate of speed than the twisting wheel. In actual practice, it is contemplated of driving the twisting wheel 11 twice as fast as the drum, but 55 obviously, the speed of rotation can be varied to suit individual requirements.

While I have shown pulley wheels, it is to be understood that the mechanical equivalents thereof can be substituted therefor, if desirable, 60 without departing from the spirit or scope of my invention.

By the use of the brackets 21 and 22, I am enabled to quickly remove the spools from the twisting wheel or quickly associate the spools therewith, and consequently, very little loss of time is experienced in renewing the spools.

Initially, the various strands of the carded cord 28 are threaded through the respective guide opening 36 and eyes 31 and through the guide 70 sleeve 38 and onto the receiving spool 12.

From the foregoing description, it can be seen that I have provided an exceptionally simple and durable form of machine for twisting cotton strands together to form a cord twist. 75

Changes in details may be made without departing, from the spirit or the scope of this invention, but what I claim as new is:—

1. A twisting machine for carded cotton strands comprising a rotatable wheel, a centrally disposed spool rotatably mounted on the wheel carrying a cotton strand, a plurality of outer spools rotatably mounted on said wheel radially disposed relative to the first-mentioned spool and carrying cotton strands, an axially disposed, normally stationary guide sleeve arranged in advance of the wheel for receiving all of said strands, means for rotating said wheel, a take-up reel arranged in rear of the guide sleeve for receiving twisted cotton strands therefrom, and means for sliding and rotating the guide sleeve in vertical and horizontal planes.

2. In a twisting machine, a take-up device for the twisted strands including a supporting base, bearing brackets carried by the base, a friction drive drum rotatably supported by said bearing brackets, spaced upright standards carried by the base, pairs of inverted U-shaped supporting members having hollow legs slidably mounted on the standards, means rigidly connecting said supporting members together for synchronous movement, a take-up reel rotatably mounted on the supporting members above the friction drum for engagement therewith, and contractile coil springs connecting the supporting members with the base.

RICHARD KOSHOSHEK. 15
